UNITED STATES PATENT OFFICE.

ELISHA N. FALES, OF BUFFALO, NEW YORK.

HAND-STAMP.

1,215,788.

Specification of Letters Patent.

Patented Feb. 13, 1917.

Application filed February 2, 1916. Serial No. 75,632.

To all whom it may concern:

Be it known that I, ELISHA N. FALES, a citizen of the United States, residing at 511 Linwood avenue, in Buffalo, county of Erie, and State of New York, have invented new and useful Improvements in Hand-Stamps, of which the following is a specification.

This invention relates to improvements in printing devices of the kind adapted for printing with ink on paper, cards, postals, letter sheets, and other surfaces by the simple manipulation of a small hand stamp with its surface properly prepared for making such impressions; one of the objects of this invention being to provide such a device which may be very simply and cheaply made, which may be readily arranged for printing reading matter, drawings, designs and the like, and which may be operated at great speed to make the desired impressions by a simple stamping operation on a sheet of paper or other surface and without the necessity of reinking between impressions. The device comprises essentially an inking pad which is backed by a hard, unyielding block or other suitable supporting surface, and means for clamping upon such surface a thin fabric which is made of fibrous material covered with a waxy coating and is adapted for the making of stencils. Such a sheet of fabric is known as a stencil sheet and in the use of my improved device the stencil sheet is first prepared with an impression of the desired reading matter, drawing, design, device or inscription on its surface, either by printing upon it with a typewriter or by writing or drawing upon it with a stylus or other implement so that the waxy coating is displaced and the fibrous material of the sheet exposed. This sheet is then clamped over the surface of the ink pad and the stamp is then ready for use, it being necessary only to press it down upon a sheet of paper or other surface when ink from the inking pad is forced through the openings in the stencil sheet and upon the paper to make the desired impressions. In this way announcements on postal cards, form letters, autographic signatures, labels, etc., may be prepared with an expense so small as to be almost negligible and if a number of impressions of any kind are desired for some particular purpose a suitable impression sheet may be easily and quickly prepared and placed upon the inking pad,

and the stamp then used to make the desired impression; after which the impression sheet may be removed and discarded and another one substituted bearing different reading matter or another design or inscription.

A device embodying the principles of this invention is illustrated in the accompanying drawings in which;

Figure 1 is a view of the device in perspective.

Fig. 2 is a top plan view thereof.

Fig. 3 is a vertical section on the line 3—3 of Fig. 1.

As shown in said drawings, in Figs. 1 to 3, both inclusive, 10 indicates a suitable support for the sheets of paper, cards, or the like, to be printed upon, one of these sheets, 11, being shown resting on its flat surface and guided by a transverse strip 12 at the end of the support 10; such strip having a groove 13 under its inside edge so that the card or sheet 11 can be placed with one edge under this groove and thus held in position for the subsequent operation as will be described hereinafter. The movable part of the stamp comprises a solid block 16 which is preferably made with its lower surface cylindrically curved, and upon this surface is fixed a somewhat yielding absorbent pad 18, of felt or other suitable material, which is designed to be saturated with printing ink. Over the inking pad 18 is placed an impression sheet 19, the latter being of well known form and comprising a fibrous sheet with a waxy coating suitable for the making of stencils. Before being placed in position over the inking pad, this stencil sheet is properly prepared with the desired reading matter or design cut into its waxy covering, and being then placed over the inking pad as shown it will permit the ink to come into contact with the paper 11 only at those places where its coating has been cut away, thus making the desired impressions on the paper. For the purpose of clamping the impression sheet or stencil sheet over the inking pad the sheet 19 is brought up over each end of the block 16, and against each of such up-turned ends of the sheet there is pressed a wire clamp 24. These two wire clamps are made alike, and, as best shown in Fig. 2, each is bent back at right angles at one end and loosely pivoted to the side face of the block 16 by means of a nail or screw 25 and an eye 26 bent in the end of the wire. The other end of the wire is bent

over at right angles as indicated at 27, to extend back against the other side face of the block 16, and thence outward at right angles, forming a projection 28 which is engaged by a hook 30 on the side of the block 16 to hold the wire in place. A shallow groove 33 across the end of the block 16 permits the sheet 19 to be kinked or creased around the wire 24, as shown in Fig. 3, and 10. affords additional clamping of such sheet.

Upon one end of the block 16 is secured a flat plate 40 which extends beyond the end of the block and is bent downward to form a flange 41, and in the upper surface of the 15 strip 12 there is provided a transverse groove 42. To the upper side of the block 16 there is also fixed a handle 43, and in the operation of the device, when the impression surface of the stamp 16 has been properly 20 prepared and a sheet of paper or a card has been placed in position on the support 10 as above described, the stamp is held in the hand and the flange 41 inserted in the groove 42 so as to properly register the 25 stamp above the paper. The stamp is then brought downward, being moved about the engaging parts 41 and 42 as a hinge until the adjacent part of its printing surface comes into contact with the surface 11, when 30 it is rocked over its entire printing surface to bring all of such surface into contact

with the paper and complete the impression, such rocking movement likewise releasing the plate 40 and permitting the stamp to be raised from the paper and the latter removed. It will be observed also that in such rocking movement of the stamp and the raising of its end which has first come into contact with the paper, the latter is prevented from sticking to the sheet 19 and 40 being raised with it by its confinement in the groove 13 in the guiding strip 12.

I claim as my invention:

In a hand stamp, the combination with a stationary supporting member adapted to 45 form a support for a sheet to be printed upon and having a guide for such sheet, of a movable member comprising a solid part having thereon an inking pad, a stencil sheet and means for securing such stencil 50 sheet to such inking pad; and engaging parts on such stationary supporting member and such movable member, such engaging parts being adapted to guide such movable member into contact with the sheet to be 55 printed upon and to become disengaged in the further movement of such movable member.

In witness whereof, I have hereunto subscribed my name this 28th day of January, 60 1916.

ELISHA N. FALES.
